UNITED STATES PATENT OFFICE

BENZION WOLF, OF CHICAGO, ILLINOIS

GARTER

Application filed March 10, 1930. Serial No. 434,571.

This invention relates to garters in general and particularly to anatomic garters. More specifically, the invention relates to improvements in garters such as disclosed and claimed in Patent No. 1,737,067 and the co-pending application, Serial No. 422,501, filed January 22, 1930, Patent No. 1,772,274.

The primary object of the present invention is to provide an anatomic garter of new and improved design and construction which has an ankle encircling band or web to conform with the ankle of a wearer, which prevents pressure from being exerted at the edges of the ankle encircling portion, and which is provided with novel means for mounting a reinforcing member or stay in position in a pocket provided for the stay.

Another object is to provide a garter which has a vertical stay arranged in a pocket, and which has means for maintaining the stay in position in the pocket to keep it from extending or projecting out of the pocket.

A further object is to provide a new and novel garter of the anatomic type which is comparatively simple in construction, which is efficient in use, and which can be readily and economically manufactured.

Numerous other objects and advantages will be apparent throughout the progress of the following specification.

The invention comprises in general a band or web which is adapted to encircle the ankle of a wearer, and a leg portion which extends upwardly from the ankle band or web. The ankle band or web is provided with a buckle of light construction, and the buckle is arranged at a specific angle so that when the free end of the band, after it is arranged in place relative to the buckle, causes the band to be tapered upwardly to conform with the shape of the wearer's ankle, and thereby eliminate the possibility of chafing and preventing the edges of the band or web from causing any discomfort to the wearer. The vertical leg portion of the garter is provided with

a pocket into which a reinforcing member or stay is received to hold the vertical leg portion in its proper position. Means are provided to maintain the stay in position in its pocket and at the same time permit the stay to be removed. This means may comprise a slidably mounted buckle which engages the vertical portion and closes the pocket, the buckle also permitting some adjustment to accommodate stays of different length. This means may also comprise a snap fastening device which has cooperating parts arranged on the vertical portion and on a button element. A clasp is provided to co-act with the button to engage and hold a sock.

The accompanying drawings illustrate a selected embodiment of the invention and the views therein are as follows:

Fig. 1 is a detail view of the improved garter arranged on the leg of a wearer and supporting a sock.

Fig. 2 is a detail elevation of the garter showing a part thereof threaded through a keeper.

Fig. 3 is a detail vertical sectional view of the garter shown in Fig. 2.

Fig. 4 is a detail perspective view of the ankle encircling band.

Fig. 5 is a view similar to Fig. 2 showing a different arrangement of the keeper.

Fig. 6 is a detail sectional view of the device shown in Fig. 5.

Fig. 7 is a detail sectional view showing a modification of the means for maintaining the stay in position in the pocket.

Fig. 8 is another modification showing the button or knob connected with the reinforcing stay.

Referring to the drawings, the numeral 1 designates a band or anklet portion which is adapted to fit around the ankle of a wearer, while the numeral 2 designates a vertical member or strip which is fastened to the ankle portion or band in any convenient manner such as by stitching 3. The

ankle band 1 may be made of any kind of material desired, elastic or otherwise, although it is preferable that it be made of a non-elastic material such as ordinary tape or webbing. The member or strip 2 may also be made of any kind of fabric desired, although it is preferable that it be made of the same kind of material as the band 1. This strip 2 is preferably made of two plies 10 of fabric 4 and 5 which are sewed or otherwise fastened together as indicated at 6. The fabric 4 is preferably cut away at 7 to provide the lower portion 8 and the extended portion 9. The strip is preferably open at 15 the top as indicated at 12, Figs. 3 and 6, in order to receive a reenforcing member or stay 13. The fabric 5 extends upwardly from the top edge 7 and provides the extended portion 9 to which a clasp 14 may be 20 attached. This clasp is adapted to cooperate with a keeper 15 which may be slidable on the folded over portion of the strip 2 as shown in Figs. 2 and 3, or it may be 25 stitched to the strip as shown in Figs. 5 and 6. The keeper 15 is preferably provided with an outstanding button or knob 16 which cooperates with the clasp 14 for fixedly securing a sock 17, Fig. 1, to the keeper 15. The clasp and the keeper with its attached knob 30 or button is preferably the conventional type employed in other kinds of garters.

A buckle 17 is provided to close the top 12 of the strip 2 whether the folded portion of the strip be threaded through the keeper 35 15 as shown in Figs. 2 and 3, or if it be stitched to the strip as shown in Figs. 5 and 6. This buckle is principally employed for closing the top of the strip to hold the stay in position in its pocket between the two fabrics 4 and 5 and to prevent movement of the stay within the pocket. Where the fabric 4 is threaded through the keeper, Figs. 2 and 3, the buckle 17 will impinge the return loop 18 and the free end 19 against the back fabric 45 5 and close the opening 12. Where the keeper is merely sewed to the strip 2 as shown in Figs. 5 and 6, the free end 20 will be pinched against the back fabric 5 and also close the opening 12 to prevent movement of the 50 stay 13.

In Fig. 7, a clasping member comprising a button element 21 and a receiving or socket element 22 is provided. The receiving element or socket is fixed to the strip while 55 the button element is fastened to the stay 13. When the clasping member is in clasped position, the stay 13 is prevented from moving in the pocket or protruding therefrom. The extension 9 may have a clasp 14 fixed 60 thereto, and the fabric 4 may have a keeper 15 fastened thereto in the manner shown in the other figures.

The device shown in Fig. 8 includes a keeper 30 which is interfittingly connected 65 to the stay 13. The keeper has a knob or

button 31 fastened thereto which cooperates with a clasp 14 which is fastened to the extension 9. A clasping element is provided to prevent relative movement of the stay with the strip 2. This clasping element comprises the button part 21 which is fastened to the keeper 30 and the socket part 22 which is fastened to the fabric 5 as shown in Fig. 8. Fastening the two parts, 21 and 22, together, thereby holds the stay 13 in proper position at all times and at the same time permits its removal when desired.

The ankle encircling band or web 1 has a buckle 40 fastened to one of its ends 41 as clearly shown in Fig. 4. This buckle is disposed at an angle to the band to cause the band to assume a conical or tapered shape when the free end 42 of the band is received by the buckle. This arrangement permits the band to conform with the shape of the user's ankle and overcomes binding and chafing.

The invention comprises a novel and improved garter of the anatomic type which 90 has means for positively securing a stay in position in its pocket. The ankle band has the buckle fastened thereto at a particular angle so as to cause the band to conform with and assume the shape of the wearer's 95 ankle, and the general arrangement and construction of the various parts provides a garter which is comfortable and light.

Changes may be made in form, construction, and arrangement of the parts without 100 departing from the spirit of the invention, or sacrificing any of its advantages and the right is hereby reserved to make all such changes as fairly fall within the scope of the following 105 claims.

The invention is hereby claimed as follows:

1. In a garment support of the class described, a flexible band adapted to be applied above and to rest upon the ankle of a wearer, a supporting means secured to and extending upwardly from said flexible band, said supporting means including an elongated fabric strip provided with an elongated pocket and a reinforcing member inserted within said pocket for lending rigidity to said supporting means, closure means extending across the upper portion of said pocket at a point adjacent the upper extremity of the reinforcing member to prevent any appreciable relative movement between the fabric strip and the reinforcing member, and a garment fastening device secured to the upper extremity of said supporting means to receive the garment to be supported.

2. In a garment support of the class described, a flexible band adapted to be applied above and to rest upon the ankle of a wearer, a supporting means secured to and extending upwardly from said flexible band,

5 said supporting means including an elongated fabric strip provided with an elongated pocket and a reinforcing member inserted within said pocket for lending rigidity to said supporting means, means shiftably mounted on said supporting means for preventing any appreciable relative movement between the fabric strip and the reinforcing member, and a garment fastening device secured to the 10 upper extremity of said supporting means to receive the garment to be supported.

15 In witness whereof, I have hereunto subscribed my name.

20 BENZION WOLF.
